CARD FEEDING MEANS

Walter J. Hausman, Westfield, N. J., assignor, by
mesne assignments, to Ralph C. Coxhead Cor-
poration, New York, N. Y., a corporation of
Delaware

Application October 23, 1931, Serial No. 570,521

10 Claims. (Cl. 197—135)

This invention relates to improvements in type-writing machines and more particularly to card feeding means therefor.

An object of the invention is to provide means which may be used with any Variotype machine to feed cards without changing the construction of the machine.

In the Variotype machine the printing instrumentalities comprise a type carrier or shuttle which may be rotated by the key levers to select the type or carry it to the printing point where a hammer co-operates with the selected type to print. A work sheet is fed vertically upwardly between the type shuttle and the hammer by suitable feed rollers arranged a considerable distance beneath the printing point.

In carrying out the invention there is provided a frame or card holder which is very thin and may be introduced between the feed rollers to be fed up and down by them with the card held thereon.

Heretofore it has been impossible to type on the lower edge of the card because the feed rollers are located considerably below the printing point.

25 A feature of the invention relates to means including a holder whereby it is possible to present the lower edge of the card or work sheet to the printing point, for typing, while the card holder is still in the bite of the feed rolls.

30 Another feature of the invention is to provide, in the card holder, a cut-out or aperture through which the printing hammer of the machine may act on the card.

Other features and advantages will hereinafter 35 appear.

In the drawings which form part of the specification

Fig. 1 is a front elevation of the carriage of the machine showing the invention applied thereto;

40 Fig. 2 is a vertical section taken on the line 2—2 of Fig. 1; and

Fig. 3 is a perspective view of the card holder.

Similar reference characters represent similar parts throughout the several views.

45 The machine includes a main frame 10, only a fragment of which is shown, having a track 11 secured thereto. A carriage 12 has a bar 13 by which it may travel back and forth on the track 11 through the medium of anti-friction balls or 50 rollers 14. The upper end of the carriage has a bar 15 engaged by a relatively fixed roller 16 and a bracket 17, to guide said carriage.

A relatively fixed feed roller 18 is rotatably supported on the carriage by a shaft 19. A re- 55 leasable feed roller 20 co-operates therewith to

feed a work sheet from a basket 21 on the carriage. The roller 20 is supported on a shaft 22 rotatably supported on two arms 23 secured to a rock shaft 24 on the carriage. A spring 25 coiled around the shaft 24 presses the roller 20 against 60 the roller 18.

The feed roller 20 may be rotated by the usual line spacing mechanism including a line space wheel 26, or by means of the usual finger wheel 27. Said feed roller may be released, for the in- 65 sertion or the removal of the work sheet, by a release lever 28 which, when actuated rearwardly about the axis of the shaft 22, engages a fixed stud 29 on the carriage to force the feed roller 20 away from the roller 18 against the action of the 70 spring 25. The stud 29 engages in a notch 30 of the lever 28 to hold the latter in its released position.

The work sheet is fed upwardly to the printing instrumentalities comprising a type shuttle 31, 75 and a hammer 32 to co-operate therewith, the printing point being some distance above the bite of the feed rollers. The machine thus far described is of the usual Variotype construction.

The card holder 35 of the present invention 80 comprises two vertical members 36 joined by a horizontal bar 37 to form a permanently flat H-shaped frame composed of sheet metal. Resilient fingers 38, suitably secured to the vertical members or arms 36, press against the upward 85 extending portions thereof to hold a card 39 thereon. The fingers 38 are also composed of sheet metal and are bent to provide shoulders 40 with which the bottom edge of the card engages to align the card on said holder. The extreme upper ends 90 of the fingers 38 are bent away from the members 35 to permit the card to be readily inserted between fingers 38 and the members 35. It will be understood that the upper portions of the arms 36 form with the cross bar 37 a cut-out through 95 which the hammer 32 may act on the work sheet.

The card holder 35 may be introduced between the feed rollers 18 and 20, while the latter are in their released position, and may be pushed downwardly until the lower ends of the vertical 100 members 35 engage the bottom of the basket 21 thus aligning the card holder on the carriage. The feed roller 20 may then be rendered effective by moving the release lever 28 forward and the card holder 35 may be subsequently fed by the 105 usual line spacing means. The usual aligning gauges 41 may also be used to align the card holder.

It will be understood that the members 36 of the card holder extend considerably below the 110

horizontal bar 36 thereof so that they may still be in the bite of the feed rollers while the bottom edge of the card is at the printing point as in Fig.

2. In other words with this arrangement it is possible to write to the bottom edge of the card even though the feed rollers are a considerable distance below the printing point.

It will further be understood that part of the card, the upper end thereof may be typed, if desired, without the use of the holder but in order to type near the bottom edge of the card or of an ordinary work sheet the holder 35 is used to control it after the lower edge passes beyond the bite of the feed rollers, said card holder thus serving as an extension for the lower end of the card. It will also be understood that the card may be mounted on the holder before or after the latter is inserted in the machine.

While the preferred embodiment of the invention has been shown it should be understood that changes in the form, arrangements, proportions, sizes and details thereof may be made without departing from the scope of the invention as defined in the appended claims.

25. I claim:—

1. The combination with a typewriting machine including a carriage, feed rollers on said carriage, and printing instrumentalities adapted to print considerably above the feed rollers, said printing instrumentalities including a hammer, the axis of the feed rollers being disposed in a plane extending at right angles to the face of the active type, of a permanently flat card holder attachable to the lower end of a card and forming an extension on the lower end of the card so that the latter may be fed by said feed rollers after the card leaves the bite of the feed rollers to present the lower edge of the card to the printing instrumentalities, said card holder having an opening behind the card through which the hammer may operate on said card.

2. The combination with a typewriting machine including a carriage, feed rollers on said carriage, and printing instrumentalities including a type wheel, and a hammer to co-operate therewith to print considerably above the feed rollers, of a metal card holder frame to be fed by said feed rollers, said frame having a cross bar, two upwardly extending arms one at each end of the cross bar, and two downwardly extending arms on the cross bar, clips co-operating with the upper arms of said frame to hold a card thereon, and means whereby the card is properly positioned on said holder, the lower arms of said frame being effective to be engaged by the feed rollers while the lower edge of the card is being presented to the printing point, the upper arms forming with the cross-bar a cut-out through which the hammer may operate against the card.

3. A permanently flat H-shaped card holder for a typewriting machine, printing instrumentalities including a hammer, said card holder having clips one at each side thereof to hold a card thereon by engaging the card near its side edges, said holder being insertable between the feed rollers of a typewriting machine to be fed thereby to the printing point, said card holder having an aperture behind the card through which the hammer may act on said card.

4. A permanently flat card holder which may be inserted between the feed rollers of a typewriting machine to feed the card in a flat condition relatively to the printing point, said card holder having devices to position the card and hold it thereon, said card holder having an ap-

erture therein through which a hammer of suitable printed instrumentalities may operate against the card.

5. A flat card holder which may be inserted between the feed rollers of a typewriting machine to feed the card in a flat condition relatively to the printing point, said card holder having an aperture therein and behind the card thereon through which a type hammer may act on the card, resilient fingers to engage only the lower portion of the card to hold the card on the card holder, and stops to engage the bottom edge of the card to properly position it on the card holder. 80

6. A flat card holder which may be inserted between the feed rollers of a typewriting machine to feed the card in a flat condition relatively to the printing point, said holder having an aperture therein through which the hammer of a typewriting machine may operate against the card, resilient fingers at opposite sides of the aperture to hold the card on the card holder, each finger having a bent portion to serve as a stop to properly position the card on said holder. 85

7. In a typewriting machine, the combination of a carriage, feed rollers on said carriage, printing instrumentalities including a hammer effective to print above the feed rollers, a detachable card holder insertable between and to be fed by said feed rollers to feed the card in a flat condition and past the printing point, said card holder having an aperture therein through which the hammer may operate against the card, means to align the card on said holder, and means to align the card holder on the carriage. 90

8. In a typewriting machine, the combination of a carriage, feed rollers on said carriage, printing instrumentalities including a printing hammer effective to print above the feed rollers, a stiff flat card holder insertable between and to be fed by said feed rollers to feed the card in a flat condition past the printing point, said card holder having an aperture therein behind said card and through which the hammer may act on the card, resilient fingers to hold a card on said holder, 105 and means on said fingers to align the card on the holder, the bottom edge of the holder engaging the carriage to align the holder on said carriage. 110

9. A card holder for a typewriting machine including printing instrumentalities having a hammer, and feed rollers located below the printing point, the card holder comprising a lower portion to form an extension of the lower end of the card to be in the grip of the feed rollers while the lower edge of the card is at the printing point, two upwardly extending arms on said lower portion to form therewith an aperture through which a hammer of the printing instrumentalities may operate against the card, and two clips 125 extending upwardly from said lower portion over the upwardly extending arms to form a receptacle for the lower end of the card, said clips being arranged to engage the card near its side edges. 130

10. The combination with a typewriting machine having feed rollers, and printing instrumentalities including a hammer, of a flat card holder to be fed by said feed rollers to present a card in flat condition to the printing instrumentalities, said holder having an aperture there- 140 through which the hammer may act on said card, and means to locate the card on said holder relatively to said aperture. 145
